UNITED STATES PATENT OFFICE.

WILLIAM CICERO SESSIONS, OF BREWTON, GEORGIA.

FILE AND CABINET.

SPECIFICATION forming part of Letters Patent No. 783,595, dated February 28, 1905.

Application filed October 7, 1904. Serial No. 227,579.

To all whom it may concern:

Be it known that I, WILLIAM CICERO SESSIONS, a citizen of the United States, residing at Brewton, in the county of Laurens and State of Georgia, have invented new and useful Improvements in Files and Cabinets, of which the following is a specification.

This invention is designed particularly for the use of druggists and physicians as a file and cabinet for prescriptions and the like and includes a novel and improved temporary file or binder adapted to hold and retain a file of prescriptions or the like and to also provide means whereby a bunch of said prescriptions may be permanently secured together and removed from the file and stored away in proper order and arrangement.

In the accompanying drawings, Figure 1 is a perspective view of the cabinet, the lower drawer being open to show bunches of prescriptions stored away therein. Fig. 2 is a perspective view of the drawer containing the prescription-file withdrawn from the cabinet. Fig. 3 is a side elevation of the prescription-file removed from the drawer. Fig. 4 is a vertical section of the prescription-file, taken through the pin or tube on which the papers are stuck. Fig. 5 is a perspective view of a bunch of papers permanently bound and removed from the file.

Referring specifically to the drawings, 6 indicates a desk or cabinet of proper form and construction to suit the needs of the user. It contains a drawer, (indicated at 7,) which holds the temporary file, as well as various other drawers (indicated at 8) for labels, special memoranda, and the like. One drawer, as indicated at 9, is preferably partitioned into compartments of proper size to receive bunches of prescriptions bound together in the manner and by the means to be hereinafter described, said drawer thereby affording a place for storage of the files as fast as they are removed from the temporary filing device contained in the drawer 7. Said temporary filing device contains a board 10, which fits within the drawer 7, but is removable therefrom as occasion requires. Said board is of a size suitable for the nature of the papers to be filed, and in a druggist's case the same will be of proper size to hold a prescription. Fixed to and projecting upwardly from this board 10

is a tube 11, of stiff or stout metal, and fitting over this tube is another tube 12, of flexible metal, which forms the permanent binder for the papers. The latter tube is slotted at both ends to form tongues 15, which may be bent over to confine the papers thereon. A removable head 13 for the pin has a shank 14, which fits within the tube 11. The tubes 12 are provided in quantities, so that one can be taken off and another substituted as fast as they become filled. Before being placed on the tube 11 the lower tongues 15 on the tube 12 are bent out to form an under clamp for the papers. The tongues at the top are bent in or gathered, so that the papers will slide onto the tube readily and said upper tongues support the pin, the head 13 of which rests thereon. At the end and each side of the board 10 are flat springs 16, which are offset inwardly at the top, as at 17, and serve to confine the papers in the file in a regular and even pile.

In the use of the device one of the tubes 12 is placed on the tube 11, and the pin-head 13 is then inserted in place. Prescriptions or other papers may then be stuck on the file. When the tube 12 is full, the pin-head is removed and the tongues 15 at the top of the tube are bent out and down upon the pile of papers. This binds them together permanently, after which they may be stored away in the drawer 9 or elsewhere for future reference. Another tube is then placed upon the file and filled in similar manner.

What I claim as new, and desire to secure by Letters Patent, is—

1. A file comprising a bottom board, a tube projecting therefrom, an outer removable tube fitting over said tube and having flexible tongues at the ends, and a removable pin having a shank fitting in said tubes and a head projecting above the same.

2. A file comprising a bottom board, a filing-pin thereon, and springs projecting from the edges of the board and arranged to confine papers thereon.

In testimony whereof I have signed my name to this specification in the presence of two subscribing witnesses.

WILLIAM CICERO SESSIONS.
